UNITED STATES PATENT OFFICE.

LEONARD E. WRAY, OF MINNEAPOLIS, MINNESOTA.

FLEXIBLE GRAIN-SPOUT.

1,192,485.

Specification of Letters Patent. Patented July 25, 1916.

Application filed January 31, 1916. Serial No. 75,205.

To all whom it may concern:

Be it known that I, LEONARD E. WRAY, a citizen of the United States, residing at Minneapolis, in the county of Hennepin and State of Minnesota, have invented certain new and useful Improvements in Flexible Grain-Spouts; and I do hereby declare the following to be a full, clear, and exact description of the invention, such as will enable others skilled in the art to which it applies to make and use the same.

My invention has for its object to provide an improved flexible metallic grain spout adapted for many uses, but especially adapted and particularly designed for use in elevators and grain storage houses for transferring grain from an elevated bin or source of supply to any one of several lower bins, with which latter, communication is easily had through openings in a floor underlying the main supply bin and overlying the several receiving bins.

Generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a view in side elevation, some parts being broken away, and some parts being sectioned, showing the improved spout; Fig. 2 is an enlarged view in side elevation of the upper portion of the spout, some parts being sectioned and some parts being broken away; Fig. 3 is a front elevation of the parts shown in Fig. 2, some parts being broken away and some parts being sectioned; Fig. 4 is a side elevation of the lower portion of the spout, including the truck for supporting the same on the underlying floor; Fig. 5 is a horizontal section taken on the line 5-5 of Fig. 4; and Fig. 6 is a front elevation of the parts shown in Fig. 4.

The numeral 3 indicates a floor which receives the multiplicity of receiving bins and is provided with openings 2 (only one of which is shown) which open into the underlying bins not illustrated.

The numeral 3 indicates the hopper-like bottom of the over head supply bin, the same, as shown, having a rectangular discharge spout 4 onto which is telescoped an upper spout section 5, the lower end of

which is cylindrical and is provided with an out-turned flange, as shown, formed by a metal ring 6 riveted thereto. The said spout section 5, at its upper edge, has an out-standing flange 7 formed by an angular metal bar riveted, or otherwise, rigidly secured thereto and constituting a lock flange for engagement with the hooked lower ends of the latches 8, the upper ends of which are pivoted to the fixed spout 4 of the hopper 3, being, as shown, directly pivoted to the lugs 9 secured on the said spout. At their intermediate portions, the latches 8 have indent cam surfaces 10 with which the lock flanges 7 may be engaged when the detachable upper spout section 5 is moved upward. By a quick upward movement of the said spout section 5, the latches 10 may be thrown outward far enough so that the said spout section 5 may then be quickly dropped down clear of the latches, and thereby easily released from the spout section.

Resting on the flange 6 of the spout section 5 and mounted to rotate around the lower end of said spout is a ring 11. Secured to the ring 11 for rotary or swiveling movements therewith around a vertical axis, is a sort of a hood 12, the sides of which are approximately flat and parallel, as shown in Fig. 3, and the other two sides of which are segments of a cylinder, the axis of which is at the axis of pivot bolts 13 applied to the central portions of the said flat sides of said hood. Working in close engagement with the outer cylindrical surfaces of the hood 12 are segmental joint plates 14 having laterally spaced flat sides that work in close engagement with the flat sides of the hood and are pivoted on the pivot bolts 13 for independent pivotal movements.

An oscillatory distributing spout 15, the lower portion of which is preferably cylindrical, and the upper portion of which is rectangular in cross section, embraces the lower edges of the joint plates 14 and is also pivoted on the pivot bolts 13. As shown, it is provided on its sides with reinforcing metal strips 16 and the bolts 13 are passed through slots 17 in the said strips and in the sides of said spout 15. At their upper ends, the strips 16 are provided with notches 18 which, when the spout 15 is moved upward in respect to the hood, will interlock with depending flanges of brackets 19 secured on the upper portions of the sides of the hood 12. The purpose of interlocking the

- brackets 19 and notches 18 is to prevent the hood and upper spout section 5 from toppling over while they are being connected to the upper spout 4, or are being disconnected therefrom. The said interlocking action will, of course, take place whenever the distributing spout 15 is forced upward, and slots permitting such movement in respect to the hood. The distributing spout is, therefore, capable of use to support the hood and upper spout 5 while the latter is being pushed upward into engagement with the latches 8, or is being disengaged therefrom by an operation already indicated.
- 15 The upper portions of the segmental joint plates are yieldingly drawn toward each other, normally to their limits, as shown in Fig. 2, by coiled springs 20 attached thereto and to the anchor brackets 19.
- 20 The distributing spout described is capable of universal swinging movements. That is, the spout 15 and hood 12 with the joint plates 14 may be rotated on a vertical axis around the upper relatively fixed spout section 5, and the said spout 15 may be freely swung in either direction for the proper delivery of grain. Hence the spout 15 is what may be termed a "double-way" spout because it may be swung in two ways, so as to throw
- 25 either one of its opposing sides downward in position to support the running grain. This practically doubles the life of the spout, and furthermore, makes it unnecessary to rotate the spout on its vertical axis in order to change its point of delivery directly from one side to the other of the projected axis of the upper and relatively fixed spout section.
- 30 When the spout 15 is vertical, or nearly so, both of the segmental joint plates 15 will remain in their uppermost positions, but when the said spout is oscillated in the one direction or the other, as, for example, to the left (see Fig. 1), the right hand joint plate
- 35 will be drawn downward, so as to maintain the joint between the hood 12 and the upper portion of the lowered side of the said spout 15. At such time, the downwardly drawn flat portion of the said joint plate spans the gap between the said hood and spout and directs the grain from the former to the latter. For all of these adjustments, a full opening for delivery of the grain from the hood to the spout is afforded and tight
- 40 dust-proof joints are maintained.

In some instances the lowermost section 15^a is supported by a so-called trolley or small wheeled truck. This wheeled truck, as shown, comprises a rectangular frame 21 and supporting caster wheels 22. The lower spout section 15 is pivoted at 23 to upwardly projected sides of a trolley spout 24 carried by the trolley frame 21 and held for vertical movements in respect thereto by studs 25. The trolley spout 24 and the

lower portion of the lower spout section 15^a are preferably rectangular in cross section, and joints between the two are maintained by pivoted spring-pressed joint plates 26. The lower end of the trolley spout 24 is adapted to be moved into and out of any one of the several floor openings 2, by a lever 27, pivoted to the sides of the trolley frame 21 and having cam-acting inner ends 28 that engage out-turned flanges of angle 75 straps 29 shown as secured to the sides of the spout section 15^a, and through which the above noted guide trunnions 25 are also passed. Of course, when the trolley spout 24 is lowered into a floor opening 2, the trolley will be located against movement. The distributing spout above described has been put into actual use and found highly efficient for the purposes had in view.

What I claim is:

85

1. The combination with an upper spout section, of a distributing spout receiving therefrom and pivotally supported at its upper end for swinging movements to either side of a vertical line, and yielding joint devices mounted on the pivotal support of said spout and extensibly connecting the opposite sides of said distributing spout to the said upper spout.

90

2. The combination with an upper spout section and a hood swiveled thereon, of a distributing spout pivoted to said hood at its upper end for swinging movements to either side of a vertical line, and segmental joint plates mounted on the pivotal connection between said distributing spout and hood and constituting extensible connections between said hood and the sides of said distributing spout.

95

3. The combination with an upper spout section and a hood swiveled thereon, said hood having opposite segmental surfaces, a distributing spout pivoted at its upper end to the sides of said hood, yieldingly held joint plates pivoted on their pivotal connection between said distributing spout and hood and having segmental surfaces cooperating with the segmental surfaces of said hood, and having depending portions arranged to be engaged by the sides of the upper end of said distributing spout, and movable downward with the downwardly moved side thereof.

100

4. The combination with an upper spout section and a hood swiveled thereon, of a distributing spout pivoted to said hood at its upper end for swinging movements to either side of a vertical line, and segmental joint plates mounted on the pivotal connection between said distributing spout and hood and constituting extensible connections between said hood and the sides of said distributing spout, the pivotal connection between said distributing spout and hood permitting vertical movements of the

105

115

120

125

130

latter, and means operative by upward movement of the distributing spout to lock the latter against pivotal movements in respect to said hood.

5. 5. The combination with an upper distributing spout, of a hood swiveled thereto, said hood having laterally spaced flat sides and opposite segmental walls, of a distributing spout pivoted to said hood with 10 freedom for limited vertical movements, means whereby upward movement of said distributing spout, in respect to said hood will lock the former against pivotal movements in respect to the latter, and joint 15 plates having laterally spaced sides pivoted on the pivotal connection between the distributing spout and hood, said joint plates having segmental portions coöperating with the segmental portions of said hood 20 and having depending portions engageable with the sides of said distributing spout for downward movement with the latter, and springs yieldingly holding said joint plates normally in their upper positions.
25. 6. The combination with a hopper spout and an upper spout section, of latches detachably interlocking the latter to the former, and which latches have releasing cams in position to be engaged by the upper spout

section on upward movement thereof, of a 30 distributing spout flexibly connected to said detachable upper spout section, and means whereby initial upward pressure on said distributing spout will interlock the same against vertical swinging movement in respect to said upper spout.

7. The combination with a hopper spout and an upper spout section, of latches detachably interlocking the latter to the former, and which latches have releasing cams 40 in position to be engaged by the upper spout section on upward movement thereof, a hood swiveled to said upper spout section, a distributing spout pivoted to said hood for horizontal swinging movements and for limited 45 vertical movements in respect thereto, means whereby initial upward movement of said distributing spout will interlock the same to said hood, and joint plates constituting extensible connections between said hood 50 and the opposite sides of said distributing spout.

In testimony whereof I affix my signature in presence of two witnesses.
